UNITED STATES PATENT OFFICE.

CARL H. HARTMAN, OF TOLEDO, OHIO, ASSIGNOR, BY MESNE ASSIGNMENTS, TO ST. REGIS PAPER COMPANY, OF NEW YORK, N. Y., A CORPORATION OF NEW YORK.

METHOD AND APPARATUS FOR VALVING BAGS.

Application filed May 10, 1928. Serial No. 276,521.

This invention relates to a method and apparatus for folding in the corners of lengths of paper tubes in order to form valves in bags made from the tubes.

5 The method and apparatus for carrying out the method disclosed and claimed in this application are particularly adapted for receiving tubes cut from a continuous length of tubing, each cut-off section having one 10 corner particularly adapted for forming a valve, this corner being differently located on successive sections. In order to accomplish this purpose the apparatus comprises two valving devices and means for directing 15 sections received from a cutting machine or similar source alternately to the two valving devices.

Details of the invention will appear as the description proceeds.

20 In the accompanying drawings forming a part of this specification, Figure 1 is a plan view of apparatus in accordance with this invention; Fig. 2 is a side elevation of the apparatus shown in Fig. 1, as viewed from 25 the right of Fig. 1; Fig. 3 is an end elevation of the apparatus, viewed from the end opposite to that which receives the sections; Figs. 4, 5 and 6 are partial sections on the lines 4-4, 5-5 and 6-6 of Fig. 1.

30 Some of the parts are omitted from the plan view and some from each of the elevations in order to more clearly disclose other parts.

The apparatus shown in the drawings is 35 mounted upon a base 10. At the receiving end of the apparatus there is a bracket 11 mounted upon the base 10 and having bearings 12. There are supplemental base sections 13 and 14 fitting upon base 10 by means 40 of dove-tail slideways 15. A screw 16 connects base sections 13 and 14 so that they may be adjusted laterally upon base 10, the screw having right and left-hand threads so that turning the screw brings sections 13 and 45 14 nearer together or separates them.

Mounted upon base 13 there is a supporting frame 17, and a similar supporting frame 18 is mounted upon base 14. Frame 17 is connected to base 13 by means of a dove-tail 50 guide 19 and frame 18 is connected to base 14 by a dove-tail guide 20. Mounted on frame 17 there is an upper table 21 having a valving device 22 arranged alongside thereof. The details of this valving device are not

disclosed in this application, as its exact construction is not a part of this invention. A valver like that disclosed in the patent to Bates et al. for method and apparatus for severing and valving bags, 1,623,228, issued April 5, 1927, is suitable for use with the present invention, although any other valver which would accomplish the same purpose may be substituted therefor.

Upon frame 18 there is mounted a table 23 on a lower plane than table 21. Alongside 65 of table 23 there is another valving device 24, the valving device 24 having the valving mechanism at the receiving end of the apparatus instead of at the other end of the apparatus, as arranged in valving device 22. 70 The arrangement of valving devices 22 and 24 might be reversed without changing the result. An upper table 25 is mounted on frame 18 in the same plane with table 21, and a similar lower table is mounted on 75 frame 17 in a plane with table 23.

Mounted on bracket 11 in bearings 12 there is a main drive shaft 26. Longitudinal drive shafts 27 and 28 are mounted in frames 17 and 18 respectively, and are driven from 80 drive shaft 26 by bevel gears 29 and 30 respectively.

Mounted upon brackets 11 and upon brackets 11^a on bases 13 and 14, there are brackets 31 adapted to support feed rollers 85 for feeding bags to the lower valver. Brackets 32 mounted upon bracket 31 support feed rollers for feeding bags to the upper valver.

The rollers mounted in bracket 31 comprise a lower receiving roller 33, a mating upper roller 34, a lower delivering roller 35 and a mating upper roller 36. A chain 37 leading from a cutting or delivering machine, not shown, operates the shaft carrying roller 95 33, and roller 34 is driven from roller 33 by gears 38. Chains 39 drive front rollers 35 and 36 from rear rollers 33 and 34 respectively. In Fig. 2 these rollers are shown feeding a bag 40 towards the lower valver. 100

Switch fingers 41 are pivoted above and to the rear of receiving rollers 33 and 34, and are operated in timed relation with the bag delivering machine by means of a rod 42. When the bags are to be delivered to the lower valver the rear ends of fingers 41 are raised out of the path of the bag, as shown in Fig. 2, and then are lowered into the path of the 105

next bag so as to guide it upward to the upper valver.

Only one pair of feed rollers is provided for the upper valver, a lower roller 43 and an upper roller 44. Roller 43 is driven by a chain 45 from roller 33, while roller 44 is driven from roller 43 by means of gears 46.

A bag 47 is fed into position on the table of the upper valver. In the somewhat diagrammatic section shown in Fig. 5, the bag is shown being fed into position. It will be seen that a pipe 48 is in position to blow against the side of the bag. The side is provided with a gusset which is spread apart by the blast of air from pipe 48 so as to pass over a fin 49 attached to the casing of valver 22. Table 21 has a beveled edge 50 beneath fin 49 for receiving the downwardly spread gusset. It will be understood that the thickness of the bag, of fin 49 and of bevel 50 are exaggerated for purposes of illustration in Fig. 5. The blow-pipe and fin are for the purpose of spreading apart the gusset so that the end thereof will be in position to enter between clamping members 51 of the valving device and pass outside of spreading members 52 of the valving device, these members 51 and 52 corresponding to similar members disclosed in the patent identified above.

Beneath table 25 there is a bracket 53 (see Fig. 4) having a slideway 54 in which there reciprocates a rod 55. A hook 56 is attached to the end of rod 55 and reciprocates in a slot 57 in the table. A pin 58 projecting from the hook rides upon a block 59 and supports the end of the hook so that it projects slightly above the table when in its position towards the valver. A spring 60 normally draws the rod and hook away from valver 22, but a roller 61 on the end of the rod contacts a cam 62 on shaft 63, which cam drives the rod towards the valver at appropriate times.

A cam 64 on shaft 26 is connected to a rod 65 which operates a lever 66 fulcrumed at 67 upon a stationary support. Lever 66 is connected to an upper lever 68 fulcrumed at 69 upon the same support and connected to a rod 70 which operates a valver-actuating lever 71. The manner in which the lever 71 may operate the valving mechanism will be readily understood from the above identified patent.

At the right of the apparatus as viewed in Figs. 1 and 3, there are rollers 72 and 73 having their upper surfaces substantially on a level with tables 21 and 25. A roller 74 is located above and in position to mate with roller 73. A frame 75 is pivoted upon the axis of roller 74 and projects towards the valver and carries a roller 76 above roller 72, while an arm 77 of the frame projects from the axis of roller 74 in the opposite direction and carries a cam roller 78 in position to be actuated by a cam 79 on a shaft 80.

Roller 74 is driven by means of a chain 81

from shaft 28, while gears 82 drive roller 73 from roller 74. Roller 72 is connected by a chain 83 with roller 73.

A chain 84 drives shaft 63 from shaft 28, and chain 85 drives shaft 80 from shaft 63.

A blow-pipe 86 is adapted to open the gusset of bag 87 as it is fed into position upon the lower valver, as will readily appear from Fig. 6.

A cam 88 upon shaft 26 operates a rod 89 leading to a lever 90 adapted to actuate valver 24.

For the most part, the driving mechanism and take-off rollers, etc., connected with the lower valving mechanism are either identical with those of the upper valving mechanism as described above, or so closely similar thereto that separate description is not necessary. Except where the separate parts of the lower valving mechanism have been separately described above, their parts are given the same reference numerals as similar parts of the upper valving mechanism described above with the addition of the letter "a" thereto.

The valving tables may be covered, if desired, with sheet metal face plates 91, so as to cover any spaces between the separated tables extending from the two side frames, and to form a substantially continuous support for the bags.

If desired, a second pair of upper rollers 92 may be mounted in bracket 32 and driven from roller 44 by means of chain 93. Belts 94 may be mounted upon rollers 44 and 92 so as to intercept the upper end of a bag and insure its entrance between rollers 43 and 44.

An upper supporting plate 95 may be mounted above each side frame and connected to bracket 32 by means of bolts 96, which may pass through elongated slots in plate 95 so as to allow adjustment of the frames longitudinally of the apparatus. Side frame 17 has its supporting members so arranged as to provide a free passage to the left of the lower valving mechanism as viewed in Figs. 1 and 3.

In the above description the feed rollers and take-off rollers have been described as though they were continuous, but it will be readily understood that each may be made in separate sections if desired. In the drawings these rollers are shown as being each in two sections. Only one hook 56 has been described, but it will be readily understood that as many as desired may be used, two being shown in the drawings.

The operation of the device may be understood from the foregoing description, but for convenience the operations will be described in consecutive order.

The apparatus disclosed in the drawings is intended for use with a cutting or feeding apparatus adapted to deliver bags in a substantially continuous stream, alternate bags being suitable for having valves folded in on differently located corners. Any desirable

feeding device may be utilized, but the apparatus is particularly designed for operation with a tube cutting machine similar to that shown in my co-pending application Serial No. 210,902, filed August 5, 1927.

As indicated during the description, the feed rolls are intended to be directly driven from the cutting or delivering machine, and likewise the guiding fingers 41 are oscillated in timed relation with the delivering mechanism. Main drive shaft 26 is also driven in timed relation with the delivering means in any suitable manner. Obviously the feed rolls and the guide fingers might also be driven from the drive shaft 26 instead of directly from the delivering means, if such method of driving were found more convenient.

It will be readily understood that as the bags are fed from the cutter in a substantially continuous line they are delivered alternately to the lower and upper set of feed rollers. Preferably the feed rollers are run at such a speed that they move the bags somewhat more rapidly than the movement of the tube entering the cutter, so that there is a sufficient space between successive bags to allow for the separation of alternate bags into different paths.

In the position of the mechanism shown in the drawings, bag 47 has just been fed into position on the upper valver, ready for the valving operation. The bag on the lower valver has had its corner tucked in, and is ready to be discharged. It will be seen that hook 56^a has been moved to the left, as viewed in Fig. 3, and pin 58^a has ridden down on the slanting end of block 59^a so that it is beneath the table and no longer interferes with lateral movement of the bag. Cam 79^a has lowered roller 76^a so as to press the bag down upon the constantly moving roller 72^a. This immediately results in the bag being moved sidewise away from the valver and towards rollers 73^a and 74^a, which receive it and discharge it to the left of the apparatus, as viewed in Figs. 1 and 3.

This operation takes place in time to move the bag on the table out of the way of the end of the oncoming bag 87. Immediately after the forward end of the oncoming bag passes rollers 35 and 36, the gusset in the side of the bag is spread by a blast of air from pipe 86. As a matter of fact, it is preferable to place rollers 35 and 36 sufficiently far from the edge of the bag so that the gusset may begin to spread before it has passed the vertical plane passing through the axes of the rollers.

The bag continues to move forward until it is discharged from rollers 35 and 36, whereupon it is in proper position longitudinally of table 23. In order to insure its being positioned snugly against the valver casing, so as to be properly positioned laterally of table 23, hooks 56^a are driven by cams 62^a against the

left side of the bag, as viewed in Fig. 3. Immediately after the bag is thus properly positioned with respect to the valver, cam 88 operates to actuate the valver and fold in the corner of the bag, in a manner which will be readily understood from the disclosure in the above cited patent. Thereafter the bag is discharged in the same manner as previously described. In the meantime, and starting immediately with the position in which the parts are shown in the drawing, the upper valver is actuated by cam 64 and the corner tucked in to form the valve. Thereafter hooks 56 are slid to the right and downwardly and rollers 76 are lowered so as to move the bag to the right out of the path of the oncoming bag 40, which is guided upward by fingers 41 to feed rolls 43 and 44. Feed rolls 43 and 44 move the bag into position longitudinally of the upper tables, and hooks 56 are then actuated to push it snugly against the valver casing. Immediately after the end of the bag passes rollers 43 and 44, a blast of air from pipe 48 opens the gusset of the bag so that it will slide over guiding fin 49 and enter between clamps 51 and move on outside of spreading members 52 of the valving device.

Air may be supplied continuously to pipes 48 and 86 if desired, but it is preferable to employ a valve which permits a discharge of air at the time needed and shuts off the supply at other times. Such a valve for pipe 48 is indicated at 97 on Fig. 1, and may be actuated in proper timed relation by shaft 80^a. The valve of pipe 86 may be similarly operated, though it is more convenient because of the location of this pipe to operate its valve from shaft 28, by means not shown, instead of from shaft 80.

It will be seen that by directing alternate bags into different paths, one above the other, and discharging them sidewise from the valver, I am able to maintain a substantially constant stream of bags from the cutter into the valver and thus perform the valving operation without any interference with the continuous passage of the tube through the cutter. It will be readily understood that in folding in a corner of a gusseted bag in the manner disclosed in the aforementioned patent, a portion of the bag material is bent into such a position that it could not move onward past the spreading device. For this reason the bag which has a valve folded in at its forward end must necessarily be moved away from the valver sidewise or in a rearward direction. For this reason the discharge sidewise from the upper valver, or the valver which folds in the forward corner of the bag, is necessarily sidewise from the valver. In the device shown the lower valver is arranged to fold in the rear corner of the bag. In order to simplify construction by the use of substantially duplicate parts, the bag is discharged sidewise from this lower

valver also, but it is obvious that it would be entirely possible to continue the motion of the lower bag endwise away from the valver if found desirable. Take-off rollers similar to those disclosed could be employed for thus moving the bag endwise if such movement were preferred.

It will be clear also that the lower valver might be constructed to valve the forward corner of the bag while the upper valver tucked in the rear corner of the bag, if such arrangement should be more convenient under any circumstances.

If preferred, the upper valver might be placed on a level with the plane in which the bags are fed from the cutter or bag delivering machine, and alternate bags deflected downward to the lower valver; or the bags might be delivered on a plane midway between the valvers and deflected first downward and then upward.

Various other changes may be made in the manipulation of the bags and in the apparatus for performing those manipulations without departing from the scope of the appended claims.

What I claim is:

1. The method which consists in feeding longitudinally a substantially continuous succession of tube lengths, deflecting successive lengths into separate paths while still running longitudinally, and tucking in one corner of each length to form a valve while it is in one of said paths.
2. The method which consists in feeding forward longitudinally a substantially continuous succession of tube lengths, different lengths having differently placed corners adapted to be tucked in to form valves, while the lengths are still running longitudinally deflecting them into separate paths so that the lengths in each path have like corners adapted to be tucked in to form valves, halting each length temporarily while in its respective path, tucking in a corner of each length to form a valve while the length is halted, and removing the length in time to make way for the next succeeding length fed into that path.

3. The method which consists in feeding forward a substantially continuous succession of lengths, deflecting successive lengths into paths in different vertical planes, and tucking in one corner of each length to form a valve while in its respective path.

4. The method which consists in feeding forward a substantially continuous succession of lengths, deflecting successive lengths into paths in different vertical planes, halting each length while in its respective path, tucking in one corner to form a valve, and thereafter moving the length forward in time to make room for the next length deflected into that path.

5. The method which consists in feeding a substantially continuous succession of lengths of tube longitudinally, deflecting successive lengths into paths in different vertical planes, halting each length while in its respective path, tucking in one corner to form a valve, and thereafter moving the length sidewise from its valving position in time to make room for the next length fed into said path.

6. In combination, means to feed a series of tube lengths in line, means to deflect successive lengths from the line into paths in different vertical planes, and means in each plane to tuck in one corner of each successive length without interrupting oncoming lengths.

7. In combination, means to feed a series of bag lengths in line, means to deflect successive lengths alternately to an upper and lower path, means in one path for tucking in a forward corner of each length passing through that path, and means in the other path for tucking in a rear corner of each length passing through that path.

8. In combination, means to feed forward a series of bag lengths in line, means to separate successive lengths and feed them forward in paths in different vertical planes, means for valving each length while in its respective plane, and means for delivering each length sidewise from the valving device.

In testimony whereof, I have hereunto signed my name to this specification.

CARL H. HARTMAN.
